Elmer Ryder

UNITED STATES PATENT OFFICE.

ELMER RYDER, OF ARGO, ILLINOIS.

COMBINED HEATER AND MUFFLER FOR MOTOR VEHICLES.

Application filed November 5, 1921. Serial No. 513,007.

To all whom it may concern:

Be it known that I, ELMER RYDER, a citizen of the United States, residing at Argo, in the county of Cook and State of Illinois, have invented new and useful Improvements in Combined Heaters and Mufflers for Motor Vehicles, of which the following is a specification.

This invention relates to a combined heater and muffler for automobiles and other motor vehicles.

One object of my invention is to combine the muffler and heater in one structure so that the two may be applied to the car as one fixture, thus reducing the cost of construction and installation, and further have the muffler serve a dual purpose, namely, to muffle the exhaust gases and to constitute the heating element for the heater.

Another object of my invention is to cast or otherwise make the muffler in one piece so that there are no joints in the structure to allow the exhaust gases to leak into the car through the heater.

A further object of my invention is to provide a damper plate for the heater and thus allow the same to be turned on and off when desired without diverting or in any way interfering with the passage of the exhaust gases through the muffler.

Another object of my invention is to provide means for allowing a draft of air to pass over the muffler when the heater is turned off and thus carry off the radiant heat from the muffler to avoid overheating it or heating the car when the heater is turned off.

A still further object of my invention is to associate the damper plate and means for allowing air to pass over the muffler so that in the operation of the former to close the heater the latter will be opened.

Other and further objects of my invention will appear from the following specification taken in connection with the accompanying drawings, in which—

Fig. 1 is a longitudinal vertical sectional view taken through a combined muffler and heater constructed in accordance with my invention, said section being taken on line 1—1 of Fig. 2;

Fig. 2 is a top plan view of the parts shown in Fig. 1, partly in section;

Fig. 3 is a side view of my device;

Fig. 4 is a transverse vertical sectional view taken on line 4—4 of Fig. 2; 55

Fig. 5 is a bottom plan view on a small scale of the muffler; and

Fig. 6 is a view of a detail of construction to be hereinafter described.

In the drawings, 1 indicates a floor board of an automobile. This is cut out to provide a rectangular opening 2 to receive the combined heater and muffler of my invention. Such device comprises a metal pan 3 having a bottom wall 4 and side and end walls 5 and 6, inclined upwardly and outwardly, as shown. An outwardly extending, horizontal flange 7 is provided about the upper edges of said walls 5 and 6, and this flange rests on the floor 1 about the opening 2 and may be secured to said floor to hold the pan 3 in place.

Extending over the top of the pan 3 is a metal frame 8 provided within its margin with a plurality of openings or holes 9 arranged in rows, as shown, so that the frame is a register. Said frame 8 is connected along one side by hinges 10, 10 with the associated side edge of the flange 7 so that the frame 8 may be raised for opening the pan. The frame 8 is provided adjacent its side opposite the hinges 10 with an undercut finger hole or recess 11 to facilitate raising and lowering the frame into and out of open and closed positions. 85

Located in the pan 3 is a muffler 12. This is a hollow conduit and has the general shape shown in the drawings. The muffler 12 is provided with a number of interior baffle walls 13, 13 staggered with respect to each other and arranged upright and joining the top and bottom walls of the muffler casting. The muffler 12 is cast in one piece, thus avoiding joints in the construction with the result that exhaust gases passing through the muffler do not leak out of the same and into the body of the car through the openings 9 in the register 8. Manifestly, there is no likelihood of smoking out the car body or having it filled with any of the objectionable exhaust gases. The muffler 12 is provided at one end with a tubular inlet fitting 14 and at the other end with an outlet fitting 15. These parts 14, 15 project outward from the pan 3 through suitable openings provided therein for that purpose and 100 105

enable pipe sections or other conduits to be connected therewith for carrying the exhaust gases from the engine and into and through the muffler 12 and out to the atmosphere.

For controlling the passage of radiant heat from the muffler 12 through the openings 9 of the register 8, I provide a damper plate 16 beneath the plate 8, as shown in Figs. 1 and 2. This plate 16 is provided with a plurality of holes or openings 17, 17 of the same size and shape as the openings 9 and arranged in the same manner. These openings 17 are adapted to be moved into and out of register with the openings 9 as the plate is slid back and forth beneath the register 8. To support the plate 16 in sliding engagement with the under side of the register 8, I provide a plurality of inwardly extending spring clips 18 secured to the under side of the register 8 and overlapping the side margins of the damper plate 16, as clearly shown in Fig. 4. The plate 16 has adjacent one end a knob 19 in an elongated slot 20 in the register 8, by means of which the plate 16 may be moved over to completely open or close the openings 9 or to partially open the same to control the amount of heat passing into the car through the register.

To hold the register 8 closed, I provide a spring catch construction, which comprises a plurality of flat spring members 21 secured to the pan 3 on the inside adjacent the swinging side edge of the plate 8. These spring members 21 have their upper edges bent or curved outward and are provided with apertures 22 to receive rounded heads 23 carried by lugs 24 depending from the under side of the register plate 8, as clearly shown in Fig. 6. This construction holds the register plate closed and prevents it from rattling during the travel of the car over the roadway and also holds the plate 8 in normally closed position. The construction, however, allows the register plate 8 to be swung upward from the pan when the plate 8 is raised. To facilitate radiating heat from the muffler 12, it is provided with a plurality of upwardly projecting fins 25, which, in the form of device shown in the drawings, extend transversely across the top wall of the muffler casing.

The muffler casing 12 is also provided with an outwardly projecting rib or flange 26 extending completely about the casing between the top and bottom walls thereof and rests against the inclined marginal walls of the pan 3, as shown in Fig. 4. This supports the muffler in the pan, and to hold the muffler from rattling and moving about the pan when a car is in motion, I secure the muffler 12 to the pan 3 by a number of screws 27 inserted through the bottom wall of the pan and into the bottom wall

of the muffler casing, as shown in the drawings.

The pan 3 is provided in its side walls 5, 5 with elongated openings 28, 28. These are normally closed by spring pressed dampers 29, 29 arranged on the outside of the pan and hinged to the walls 5, 5, as shown. When the damper plate 16 of the register is closed, radiant heat from the muffler 12 is shut off from entering the car, and at that time it is advisable to have the dampers 29, 29 open to permit a current of air to pass over the muffler 12 to carry off the radiant heat, thus preventing overheating of the muffler while the heater is closed.

To open the dampers 29, 29 automatically upon moving the plate 16 into closed position, I provide each damper 29 with a plurality of arms 30. These extend into the pan 3 through the slots or openings 28, as shown in Fig. 4, and have their inner ends arranged in the path of movement of the lugs 31 depending from said plate 16. The lower surfaces of these lugs 31 are cam shaped or inclined lengthwise of the plate 16 and moved by the plate 16 into engagement with the arms 30 swing the dampers 29 outward to open the slots 28. This happens when the plate 16 is moved into closed position and said dampers 29 are held open as long as the plate 16 is in closed position. When the plate 16 is moved into open position, the lugs 31 are moved out of contact with the arms 30 by the springs associated with the dampers 29, the latter being swung into closed position and normally maintained in that position while the heater is in use. Should the register plate 8 be raised while the damper plate 16 is in closed position, the lugs 31 would be lifted from the arms 30 and the dampers 29 will close. But on closing the plate 8, the lugs 31 strike the arms 30 and again open the dampers 29.

The rib 26 on the muffler 12 in contacting with the marginal walls of the pan 3 prevents dust and articles dropped into the pan through the openings 9 and 17 of the register from getting under the muffler 12 and being in an inaccessible position. These articles may be readily reached for removal from the pan by swinging the register frame 8 upward. Furthermore, the pan 3 may be swept out or cleaned when the register frame 8 is opened, by reaching into the pan and sweeping the accumulated dust and dirt out of the pan through the openings 28 when the dampers 29 are held in open position. This therefore permits maintaining the heater clean and sanitary and furthermore enables cleaning out of the heater to be done with dispatch and ease as the parts are readily accessible for cleaning purposes when the register plate 8 is swung into open position.

To insulate the muffler 12 from the bottom of the pan 3, a packing 33 of insulating material, such as asbestos, is interposed between the parts and also forms a resilient support 5 for the muffler in the pan.

By the construction described, the heater and muffler are installed as a unit or fixture, thus allowing the muffler to be used as a means for supplying heat to the car, while 10 at the same time acting as a muffler. This therefore eliminates the expense of having two separate parts for this purpose as heretofore, namely, a heater and a muffler both separate, and also minimizes the expense of 15 installing the parts in the car as the two are combined and are installed both as a single unit or fixture. The register 8 having the damper plate 16 permits the latter to be turned off when desired and also permits a 20 regulation of the amount of heat passing into the car. This also makes possible the use of the heater and muffler combined, as the heat in the muffler may be shut off in the car by closing the plate 16. The radiant heat from 25 the muffler is carried off through the openings 28 and thus does not find its way into the car to inconvenience or make uncomfortable the occupants thereof when the heater is not in use. To aid in this, the plate 16 30 carries a sheet of asbestos 32 on its under side.

By the construction described, the heater may be utilized in the winter-time or in cold 35 weather and may be readily turned off in summer-time or when not desired, without interfering with the function of the muffler as such.

While I have shown and described herein in detail a combined heater and muffler em-

bodying the features of my invention, it is 40 of course to be understood that the details of construction and arrangement of parts shown may be variously changed and modified without departing from the spirit and scope of my invention. 45

I claim as my invention:

1. A device of the character described, comprising a register plate, a pan beneath the same, a muffler in said pan for radiating heat through said register plate, a slidably mounted damper plate beneath said register plate for controlling the passage of heat therethrough, said pan having openings on opposite sides thereof to permit a current of air to pass through the pan and over the 55 muffler, spring pressed dampers for normally closing said openings, arms on said dampers, and means carried by said damper plate to engage said arms upon moving said damper plate into closed position for opening said spring pressed dampers. 60

2. A device of the character described, comprising a register plate, a pan beneath the same having a bottom and upwardly extending marginal walls, a muffler in said pan for radiating heat through said register plate, said muffler having a projecting rib extending about the same and engaging against the marginal wall of said pan above the bottom thereof, said register plate being 65 hinged to said pan, and a damper plate slidably mounted beneath said register plate and carried thereby for controlling the passage of heat therethrough. 70

In testimony that I claim the foregoing 75 as my invention, I affix my signature this 1st day of November A. D. 1921.

ELMER RYDER.
